UNITED STATES PATENT OFFICE.

JOHN U. BARR, OF NEW YORK, N. Y.

DESIGN FOR A PINCUSHION.

No. 38,630.

Specification for Design.

Patented June 18, 1907.

Application filed May 7, 1907. Serial No. 372,444. Term of patent 3½ years.

To all whom it may concern:

Be it known that I, JOHN U. BARR, a citizen of the United States, residing at New York city, county and State of New York, have invented a certain new, ornamental, and original Design for Pincushions, of which the following is a specification, reference being had to the accompanying drawing, forming part thereof.

The figure is a front elevation of a pincushion showing my new design printed on a card the part between skirt and shoe being raised from the plane of the sheet to form a cushion for pins, and padded and covered with fabric.

I claim:

The ornamental design for a pin-cushion as shown.
